UNITED STATES PATENT OFFICE.

OLIVER WESTON, OF WARRENSVILLE, OHIO.

GAME.

Application filed April 7, 1926. Serial No. 100,303.

This invention relates to games and more particularly to a dial and pivotally supported arrow adapted to be spun for designating upon stopping a certain play or name on the dial.

The main object of the invention is to provide a game of said character, in which is provided a base for supporting a removable dial and simple means for securing the dial 10 to the base. The purpose of providing a removable dial is to make it possible to use in connection with one base different dials for playing various games.

With the above and other objects in view, 15 the invention will be hereinafter fully described and illustrated in the accompanying drawings and the novel features thereof will be distinctly pointed out in the appended claims.

20 In the drawings similar characters of reference are used to designate corresponding parts.

Figure 1 is a sectional elevation taken on line 1—1 of Fig. 2, of a game constructed 25 in accordance with my invention.

Fig. 2 is a plan view of Fig. 1.

In order that the invention may be clearly understood, the same is illustrated in the drawings and will be hereinafter fully described as pertaining to a base-ball game, 30 but it will be understood that the invention is applicable to any game in which a disk or dial having designations thereon and a spinning arrow or the like is used to indicate, upon stopping, a certain play or name or 35 the like on the dial.

Referring to the drawings 1 represents a circular base preferably made of sheet metal and consisting of a top 2 and an outwardly 40 turned peripheral bottom flange 3. The top 2 is dished and its center depressed at 4 to provide a chamber 5. A threaded screw 6 serving as a post passes upwardly through an opening 7 of the top, and a nut 8 on said 45 screw within said chamber holds the screw securely in an upright position. A disk or dial 9 is adapted to rest upon said top 2 and is secured thereon by means of a flanged nut 10 on the screw 5. The upper portion of the 50 screw 5 is reduced in diameter at 11 and terminates in a point 12. A head 13 of suitable form and weight terminates in a central

boss 14 for convenience in spinning the head and having a central recess 15 in its underside for receiving and clearing the flanged 55 nut 10 and an opening 16 for receiving the upper portion 11 of the screw 5, is rotatably mounted upon the point 12 of the post. An arrow 17 is fixed to the head 13 for the purpose of indicating, after the head has been 60 spun, a particular designation upon the disk or dial 9.

The disk or dial 9 is suitably marked off by radiating lines as 18, and in the spaces between said lines are suitable designations 65 19 as shown. The designations shown are for a base-ball game but this is only by way of illustration, and it is to be understood that any other designations for games or the like may be marked upon the disk or dial. 70 When it is desired to remove one disk or dial and replace another upon the top 2 of the base, it is only necessary to remove the head 13 by lifting it off the post 5, then turning off the flanged nut 10 and lifting off 75 the dial or disk. Openings 20 are provided in the top 2 for inserting the finger underneath the disk or dial to force the same thereoff.

Having fully described my invention what 80 I claim is:

1. In a game, the combination of a base, the base having a top, a threaded post fixed in the top, a nut mounted upon the post and adapted to engage a dial resting upon 85 the top of the base, and a head pivotally supported upon the post.

2. In a game, the combination of a base, the base having a top, a threaded post fixed in the top, a nut mounted upon the post and 90 adapted to engage a dial resting upon the top of the base, a head pivotally supported upon the threaded post, and the head having a recess for clearing said nut.

3. In a game, the combination of a base, the base having a top, a threaded post fixed in the top, a nut mounted upon the post and adapted to engage a dial resting upon the top of the base, a head pivotally supported 95 upon the threaded post, the head having a recess for receiving said nut and an arrow fixed to the head.

4. In a game, the combination of a base, the base having a top, the top being dished,

the central portion of the top being depressed to provide a chamber, the top being provided with an opening at its center, a threaded screw passing through the opening, 5 a nut on the threaded screw within said chamber for securing the screw to the top, a flanged nut on the screw adapted to engage a disk resting upon said top, a head, the head being pivotally supported upon said screw, the head being provided with a recess 10 for clearing said flanged nut, and an arrow fixed to said head.

In testimony whereof I affix my signature.

OLIVER WESTON.
